Renewed November 5, 1934

14 Claims. (Cl. 308—4)

This invention relates to well drilling equipment and relates more particularly to a protective bearing device for use on a rotary well drilling string. It is a general object of the present invention to provide a simple, practical and effective drill pipe protector.

In the rotary method of well drilling, the drilling tool is operated on the lower end of an operating string made up of lengths of drill pipe connected by couplings and tool joints. A deep well is seldom straight and vertical and when the drilling string or operating string is rotated, it engages the well casing and the walls of the open well bore, with the result that the couplings and joints in the string become worn, and the well casing is damaged. Devices known as casing protectors or drill pipe protectors are often arranged on a rotary drilling string to prevent excessive wearing of the casing and parts of the string, and to centralize the string in the well. The majority of the drill pipe protectors that have been introduced have been complicated and are not altogether satisfactory in operation, as they have been constructed with the intention of being immovably fixed on the drilling string. Drill pipe protectors of the class just mentioned are usually difficult to assemble on the drilling string and are often sectional so that they are subject to failure and detachment from the string. A class of drill pipe protectors has been developed in which the body is proportioned so as to be movable on the drill pipe between spaced couplings of the string, but cannot be sprung over the couplings, so that its arrangement on the string necessitates the disconnection of a coupling from a length of drill pipe. The types of drill pipe protectors that are free to shift on the drill pipe are of greater specific gravity than the circulation fluid or rotary mud so that they slide down the string and rest on the upper ends of the couplings or joints and do not protect the lower ends of the couplings or joints which are the most subject to wear.

An object of the present invention is to provide a drill protector that may be easily and quickly arranged on a drilling string between spaced projecting parts in a manner so that it cannot become displaced or shifted from its position between said parts.

Another object of the invention is to provide a drill pipe protector that has a lower specific gravity than the usual rotary mud and that is free to shift on the drilling string between spaced couplings, or the like, so that it may float up against a coupling and effectually prevent its engagement with the well casing or wall of the well bore.

Another object of the invention is to provide a drill pipe protector that may be free to turn and/or shift longitudinally between two project-

ing parts on a drilling string, but cannot possibly become displaced from between the projecting parts. It has been found that a drill pipe protector operates more efficiently when it is free to move on the drilling string, but considerable difficulty has been encountered in providing a drill pipe protector that is free to turn or shift on the pipe and which will not become displaced from its proper position on the pipe. In accordance with the present invention, the drill pipe 10 protector is free to turn and to shift between two spaced projecting parts on the drilling string but cannot possibly become displaced from its proper position on the string.

Another object of the invention is to provide a 15 drill pipe protector of the character mentioned that includes a continuous or unbroken body of resilient wear-resisting material projecting from the drilling string and adapted to engage the wall of the well bore or the well casing, thereby 20 preventing contact of adjacent couplings or tool joints with the walls of the well or with the well casing.

Another object of the invention is to provide a 25 drill pipe protector including an annular or tubular body of resilient wear-resisting material such as a rubber composition, and a sectional substantially rigid core or reinforcement embedded in said resilient body whose sections may be disconnected or unlocked at adjacent edges, to permit the resilient body to be expanded and sprung over a shoulder or coupling on the drilling string, and thereafter dependably locked together to prevent expansion of the resilient body so that 30 the body may be effectively and positively retained between two such shoulders or couplings 35 on the string.

It is another object of the invention to provide a 40 casing protector or drill pipe protector including an annular to tubular body of rubber composition or other resilient material presenting a continuous or unbroken outer surface for contacting with the well casing or well bore, and a rigid or substantially unyielding reinforcement 45 entirely embedded in the resilient body.

Another object of the invention is to provide a 50 drill pipe protector of the character mentioned that is simple and inexpensive of manufacture.

Other objects and features of the invention will be best and fully understood from the following detailed description of typical forms and applications of the invention, throughout which description, reference is had to the accompanying drawings, in which:

Fig. 1 illustrates one embodiment of the present invention arranged on a sub or connecting member in a portion of a drilling string operating in a well bore. Fig. 2 is an enlarged vertical detailed sectional view of the form of the invention illustrated in Fig. 1, showing it ar- 55 60

ranged on another form of sub. Fig. 3 is a view similar to Fig. 2 illustrating the manner of passing or springing the body of the protector over one of the shoulders of the sub. Fig. 4 is a trans-
5 verse detailed sectional view taken as indicated by line 4-4 on Fig. 2. Fig. 5 is a prospective view of the core or reinforcement. Fig. 6 illustrates the protector mounted on a length of drill pipe between two couplings. Fig. 7 is a front
10 elevation of a form of reinforcement involving a modified type of pin for locking together the sections of the reinforcement, and Fig. 8 is a fragmentary longitudinal detailed sectional view of another form of the invention.

15 The embodiment of the invention illustrated in Figs. 1 to 5 inclusive of the drawings, includes, generally, a sectional annular reinforcing core or reinforcement 10, means 11 for connecting the sections of the reinforcement 10, and a continuous or unbroken annular body 12 of resilient material surrounding or encasing the reinforcement 10.

The reinforcement 10 is an annular or tubular assembly, and is entirely embedded in the body 12. When the protector is in its operative position on the drilling string, the sections of the reinforcement 10 are connected by the means 11 so that the reinforcement is an unyielding assembly operating to positively prevent excessive expansion and flexing of the body 12. In practice, the reinforcement 10 is operable to prevent the body 12 from springing or passing over a projecting shoulder or coupling on the drilling string. In accordance with the broader aspects of the invention, the reinforcement 10 may consist of any suitable number of sections. In the particular form of the invention being described, there are two like or complementary sections 13 forming the reinforcement 10.

The sections 13 are preferably formed of a light weight sheet metal such as sheet duralumin, or the like. The sections 13 are of a suitable gage and are preferably sufficiently rigid when connected by the means 11 to effectively strengthen and reinforce the body 12. The two sections 13 of the reinforcement are each substantially 180° in horizontal cross section so that they form a tube or tubular structure when assembled. The reinforcing core or reinforcement 10 is of a suitable length, its length of course, depending upon the length of the body 12. In accordance with the invention, the sections 13 of the reinforcement 10 are perforated or provided with a plurality of spaced openings. In the particular case illustrated in the drawings, each section 13 is provided with a multiplicity of spaced round openings 14, and a plurality of comparatively large openings 15. The openings 15 are varied in size, and are rectangular or diamond shaped and positioned so that their greatest diagonal dimensions extend longitudinally of the sections 13. The openings 14 and 15 are provided in the sections 13 to lighten the reinforcement 10 and to insure a more perfect bond or connection between the material forming the body 12 and the sections 13 as will be more fully described.

The means 11 is provided to rigidly connect the adjacent vertical edges of the two reinforcing sections 13. In the form of the invention being described, the means 11 are releasable. The means 11 include meshing or overlapping parts 17 on the adjacent vertical edges of the two reinforcing sections 13. The meshing or over-lapping parts 17 are preferably integral with the sections 75 13 and the material forming the parts 17 is looped

or bent back upon itself to provide vertical openings 18 through the parts 17. The openings 18 may be horizontally elongated and may have substantially parallel vertical side walls. The material constituting the meshing parts 17 is bent inwardly against the inner sides of the sections 17 and the abutting parts are connected by rivets 19, or the like. The openings 18 on each set or series of meshing parts 17 are in vertical alignment when the two sections 13 are assembled as illustrated throughout the drawings. In the particular construction being described, the parts 17 have suitable clearance with one another and notches 20 are provided in the vertical edges of the sections 13 between the spaced parts 17.

Pins 22 normally extend through the openings 18 of the two sets or over-lapping parts 17 to rigidly connect the two reinforcing sections 13. In accordance with the invention, the pins 22 are adapted to be passed through the sets of openings 18 to connect the adjacent vertical edges of the sections 13 when the two sections are assembled prior to the molding of the body 12 on the sections. The pins 22 are shaped and proportioned so that they may be readily passed or driven through the openings 18 and so that they may be readily removed from the openings as will be subsequently described. If desired or found practical bent over portions or heads 23 may be provided on the upper ends of the pins 22 to limit the inward or downward movement of the pins and the pins 22 may be proportioned so that they have portions 24 projecting from the lower edge of the body when their heads 23 are resting on the upper end of the body 12. It will be apparent how the pins 22 effectively connect the vertical edge portions of the sections 13 so that the assembly of the sections constitutes a rigid or unyielding reinforcement for the body 12.

The body 12 is adapted to shiftably engage the part of the drilling string on which the protector is arranged and projects from the string so that it may engage the well casing or the walls of the well bore to prevent engagement of adjacent projecting parts on the string, such as couplings or joints, from contacting with the well casing or the walls of the bore. The body 12 is resilient, being formed of a rubber composition or the like. It is a feature of the invention that the protector is free to float in the rotary mud. As described above, the reinforcement 10 is formed of a very light weight metal and the assembly of the body 12 and reinforcement 10 constituting the protector has a specific gravity lower than the usual or typical rotary mud circulated through the well in the rotary method of well drilling. The body is an integral continuous or unbroken member encasing or surrounding the reinforcement 10. The body 12 is tubular and is molded or vulcanized directly on to the reinforcement 10. In accordance with the invention the body 12 is molded on the reinforcement 10 when its sections 13 are connected by the pins 22 in the manner illustrated in Fig. 5 of the drawings. The resilient body 12 is proportioned so as to be shiftable on the part of the drilling string on which the protector is positioned and is comparatively thick so as to project a substantial distance from the said part of the drilling string and effectively prevent adjacent metallic parts of the string from contacting with the well casing or walls of the well bore. In the particular embodiment of the invention illustrated in the drawings, the exterior 25 of the body 12 is smooth and cylindrical, it 75

being understood that the body may be provided with any desirable or suitable form of external surface. The opposite ends of the body 12 may be flat and normal to the longitudinal axis of the 5 protector and may be provided with bevelled annular corner portions 26a.

In accordance with the broader aspects of the invention, the protector may be mounted on any 10 part of the drilling string and may be rotatable and shiftable longitudinally on the string, or may be positioned between two shoulders or projecting parts so as to be held against longitudinal shifting but be free to rotate or to remain stationary 15 relative to the rotating string. It may be found desirable to provide a plurality of the protectors on the drilling string spaced so as to effectively 20 prevent engagement of the projecting parts of the string with the casing or walls of the open well bore. Fig. 1 of the drawings illustrates the 25 protector mounted on a connecting member or sub 26. The sub 26 is provided at its upper end with a socket portion or enlarged portion 27, presenting at its lower end a downwardly facing shoulder 28 and provided at its upper end with a 30 tapered socket 29 for receiving the screw threaded pin 30 of a tool joint section 31. A socket portion 32 is provided on the lower end of the sub 26 and has a threaded socket 33 for receiving the 35 threaded end portion of a length of drill pipe P. The upper end of the portion 32 presents an upwardly facing shoulder 34. The body 12 of the 40 protector provided by the present invention surrounds the portion of the sub 26 between the spaced shoulders 28 and 34. In accordance with the 45 particular application of the invention illustrated in Fig. 1, the body 12 is proportioned so that it may have little or no longitudinal movement on the sub 26 having its opposite ends adjacent or in contact with the two shoulders 28 and 34. The 50 body 12 may be freely rotatable on the sub 26, that is, it may rotate relative to the sub or may not rotate during rotation of the string. In accordance with the invention, the body 12 is proportioned so as to project outwardly beyond the portions 27 and 32 of the sub and thus prevent engagement of these parts with the wall of the well bore. While we have illustrated the device 55 mounted on a portion of the drilling string operating in an open part of the well, it is to be understood that the protector may be positioned on a part of the string operating within the well casing.

Figs. 2, 3, and 4 of the drawings illustrate the body 12 of the protector on a sub 35. The sub 35 is provided at its upper end with a tapered screw threaded pin 36 adapted to be received by the 60 socket of a tool joint section and is provided at its lower end with a tapered threaded socket 37 for receiving the pin of a tool joint section. An annular enlargement 38 is provided on the base of the pin 36 and presents a downwardly facing shoulder 39. The lower portion 40 of the sub 35 is of enlarged diameter and its upper end presents an upwardly facing shoulder 41. The sub 35 illustrated has a comparatively short upper enlarged portion 38. The body 12 of the protector 65 is mounted on the sub 35 between the spaced opposing shoulders 39 and 41. The shoulders operate to prevent longitudinal shifting of the protector, it being understood that the protector may be proportioned so as to have limited longitudinal movement on the sub if found desirable. The body 12 of the protector may be free to turn or 70 rotate on the sub 35 or to remain stationary relative to the rotating sub 35. The resilient pro-

5 tector body 12 projects outwardly beyond the portions 38 and 40 of the sub and prevents their contact with the well casing or walls of the well bore.

Fig. 6 of the drawings illustrates a protector 10 mounted on a length of drill pipe P'. The body 12 of the protector is freely rotatable and shiftable longitudinally on the drill pipe P'. The couplings 43 on the opposite ends of the length of pipe P' operate to limit the longitudinal shifting of the body 12. As the body 12 projects a substantial 15 distance from the drill pipe P', it positively prevents engagement of the pipe and pipe couplings 43 with the well casing or walls of the well. The 20 protector in being of less specific gravity than the rotary mud is free to float upon the pipe P' to a 25 position immediately below the upper coupling where it effectively prevents contact of the coupling with the casing or wall of the well bore. In accordance with the usual practice the circulation fluid or rotary mud is circulated downwardly 30 through the drilling string under pressure and discharges into the well at the lower end of the string to flow upwardly through the well. The 35 rotary mud flowing upwardly through the well aids in moving the buoyant protector upon the 40 string and in maintaining it adjacent the lower end of a joint or coupling 43.

In manufacturing or assembling the drill pipe 45 protector provided by the invention, the two sections 13 of the reinforcement 10 are first assembled and connected together by means of the pins 22. The body 12 of rubber composition, or the like, is then vulcanized or molded directly on the 50 sectional reinforcement 10. After molding of the body 12 on the reinforcement, the pins 22 may be pulled or driven out of the openings 18. The 55 heads 23 of the pins may project from the upper end of the body 12 while the lower end portions 24 of the pins may project from the lower end of the body so that the pins are readily engageable 60 for withdrawal or removal. In arranging or assembling the protector on the part of the drilling string, either one or both of the pins 22 are removed to permit the body 12 to be stretched or 65 expanded. When one or both of the pins 22 have been removed, the body 12 may be readily sprung over a projection or coupling on the string. Fig. 3 of the drawings illustrates the manner of passing or springing the body 12 over the enlarged portion 38 of the sub 35. It will be apparent 70 how removal of the pins 22 permits the resilient body 12 to be stretched or expanded adjacent the lines of connection of the two reinforcement sections 13. After the body 12 has been passed or 75 sprung over the projection 38 or other projecting part its resiliency brings it back to its normal size so that the pin or pins 22 may be again passed or driven through the openings 18 to rigidly connect the reinforcement sections 13. In practice, 80 where the shoulder or projecting part over which the body is to be sprung is comparatively short or comparatively small in diameter, it may be necessary to remove only one pin 22. Where one pin 22 is removed to allow spreading of the body 85 over a projecting part, the body is free to expand or stretch at the disconnected edge portions of the sections 13 and the sections 13 are free to pivot somewhat about the remaining pin 22. After the protector has been sprung into position 90 between two projecting parts of the string, for example, between the two projecting portions 38 and 40 of the sub 35, the removed pin or pins 22 are again driven or passed through the openings 18 and the lower projecting portions 24 of the pins 95

may be bent over to positively prevent accidental displacement of the pins.

The substantially rigid or unyielding assembly of the two rigidly connected reinforcement sections 13 effectively prevents spreading or expansion of the body 12 so that the body cannot become displaced from between the two projecting parts of the string. The reinforcement 10 does not in any way interfere with the free movement 10 of the protector, that is, it does not change the proportions of the body 12, and does project from the body so as to engage parts of the string, well casing, or the well bore. The sections 13 of the reinforcement are entirely embedded or encased 15 in the material forming the body 12 and are therefore not subjected to distortion or breakage. The plurality of openings 14 and 15 in the sections 13 become filled with the material forming the body 12 when the body is molded on the 20 reinforcement 10 so that the body is effectively bonded with the reinforcement and the portions of the body at the inner and outer sides of the sections 13 are integrally connected. When it becomes desirable or necessary to remove the 25 protector from the drilling string, the lower end portion 24 of one or both of the pins 22 may be straightened to permit the pin or pins to be driven out of the aligned openings 18. After removal of the pin or pins 22 the body 12 may be expanded 30 or stretched so as to be sprung over the projecting part such as the part 38 and thus removed from the sub or other part of the drilling string.

Fig. 7 of the drawings illustrates a modified or alternative means 11^a for locking together the 35 vertical edge portions of the reinforcement sections 13. The projecting and meshing parts 17 at the vertical edges of the sections are brought into mesh so that their openings 18 are in vertical alignment. A pin 50 is provided to cooperate 40 with or pass through each set or series of aligned openings 18. In accordance with the form of the invention illustrated in Fig. 7 of the drawings, the pin 50 cooperates with the meshing parts 17 in a manner so that it cannot become displaced, 45 thereby dependably locking the sections 13 together. The pin 50 is provided at one vertical edge with projecting parts or portions 51, and is provided at its opposite vertical edge with projecting portions 52. The projecting portions 51 50 and 52 on the opposite vertical edges of the pin 50 are offset or staggered so as to be out of transverse or horizontal alignment. The projecting portions 51 and 52 are spaced and proportioned so as to be within the openings 18 of alternate portions 55 17. The lower corners 53 of the parts 51 and 52 are bevelled or inclined downwardly and inwardly.

When the pin 50 is passed into the openings 18 of the meshing parts 17, the projecting portions 51 and 52 operate to lock the pin against 60 displacement. The lower end portion of the pin 50 that enters the opening 18 of the upper-most part 17 is free to pass through to the opening 18 of the next part 17. The lower corner of the lowermost projecting portion 52 then strikes the upper outer edge of the opening 18 in the second portion 17, causing the resilient material forming the body 12 to yield or give. A suitable force operates to bring about this yielding of the body 12 so that the entering end of the pin passes 65 through the opening 18 in the second portion 17. Upon the entering end of the pin passing into the opening 18 in the third portion 17, the bevelled lower corner 53 of the lowermost projection 51 contacts with inner upper edge of 70 the opening 18 in the second portion 17 causing 75

yielding of the material of the body 12. From the above it will be apparent how the pin 50 may be driven through the openings 18 to the position illustrated in Fig. 7. After the pin 50 has been fully driven through the openings 18, the upper ends of the projecting parts 51 and 52 are adapted to engage the lower ends of the meshing parts 17 to positively prevent withdrawal of the pin. It is to be understood that pins 50 of the character illustrated in Fig. 7 of the drawings are to be used to connect the sections 13 when the protector is positioned on the drill pipe or drill string, and are not to be used when the sections 13 are initially connected for molding of the body 12 on the reinforcement 10. The means 11^a illustrated in Fig. 7 is operable to dependably and positively lock the two reinforcement sections 13 together to positively maintain the body 12 in its proper position on the drilling string. 20

Fig. 8 of the drawings illustrates a modification of the invention in which the opposite sides of the reinforcement sections 13^a are roughened or provided with a plurality of projections or burrs 60. The projecting burrs 60 may be formed by punching or driving a suitable tool through the walls of the sections 13^a which produces openings 61 in the sections. In accordance with the form of the invention illustrated in Fig. 8 of the drawings, the body 12^a includes an outer 30 tubular part 62 surrounding the sections 13^a and an inner tubular part 63 within the sections 13^a. The two parts 62 and 63 of the body 12^a are vulcanized together on to the sections 13^a. The provision of the openings 61 permits the effective 35 vulcanizing together of the two body parts 62 and 63, and insures the proper bonding of the body parts 62 and 63 with the sections 13^a. The projections or burrs 60 at the openings 61 become embedded in the body parts 62 and 63 and thus 40 aid in connecting the body parts with the metallic reinforcing sections 13^a.

Having described only typical preferred forms of our invention we do not wish to be restricted or limited to the specific forms or applications herein set forth, but wish to reserve to ourselves any variations or modifications that may appear to those skilled in the art or fall within the scope of the following claims.

Having described our invention, we claim: 50

1. A protective bearing device for use on a drilling string including, an unbroken annular body of resilient material adapted to surround a part of the string, a sectional reinforcement for the body, and means connecting the sections of the reinforcement to render the reinforcement substantially rigid, thereby preventing springing of the body over a projection on the string. 55

2. A protector for use on a drilling string having spaced projections, said protector including, an unbroken annular body of resilient material adapted to be sprung over one of said projections to a position on the string between said projections, substantially rigid sections embedded in the body and having adjacent ends unconnected during said springing of the body over the projection, and means for connecting said ends of the sections to prevent subsequent expansion of the body. 60

3. A protector for use on a drilling string having spaced projections, said protector including, an unbroken annular body of resilient material adapted to be sprung over one of said projections to a position on the string between said projections, substantially rigid sections completely 65

5 embedded in the body and having adjacent ends relatively movable during said springing of the body over said projection, and means for rigidly connecting said ends of the sections to prevent subsequent radial expansion of the body.

4. A well drilling string having longitudinally spaced projecting parts, a resilient continuous annular body adapted to be sprung over one of said parts to a position on the string between said parts, and means in the body for preventing radial expansion of the body after it has been positioned between said parts.

5. A well drilling string having longitudinally spaced projecting parts, a resilient continuous annular body adapted to be sprung over one of said parts to a position on the string between said parts, and means in the body for preventing radial expansion of the body after it has been positioned between said parts, said means including, substantially rigid members embedded in the body, and means for connecting said members to form an annular rigid assembly.

6. A protector for use on a string of equipment operating in a well and having longitudinally spaced projecting parts, said protector including, a resilient continuous annular body adapted to be sprung over one of said parts to a position on the string between said parts, and means for preventing displacement of the body from between said parts including substantially rigid members reinforcing the body, and removable elements for rigidly connecting said members whereby the members form an annular assembly preventing radial expansion of the body.

35 7. A protector for use on a string of equipment operating in a well and having longitudinally spaced projecting parts, said protector including, a resilient unbroken annular body adapted to be sprung over one of said parts to a position on the string between said parts, and means for preventing displacement of the body from between said parts including, substantially rigid arcuate members associated with the body, projections on the longitudinal edges of the members, and elements for cooperating with the projections on adjacent edges of the members to rigidly connect the members to form a rigid annular assembly.

8. A protector for use on a string of equipment operating in a well and having longitudinally spaced projecting parts, said protector including, a resilient unbroken annular body adapted to be sprung over one of said parts to a position on the string between said parts, and means for preventing displacement of the body from between said parts including substantially rigid members molded in the body, projecting portions on the vertical edges of the members having vertical openings, and pins adapted to be passed through the openings of said portions on adjacent edges of the members to rigidly connect the members.

9. A protector for use on a string of equipment operating in a well and having longitudinally spaced projecting parts, said protector including, a resilient unbroken annular body adapted to be sprung over one of said parts to a position on the string between said parts, and means for preventing displacement of the body from between said parts including, substantially rigid members 65 molded in the body, projecting portions on the

vertical edges of the members having vertical openings, said portions on adjacent edges of the member meshing one between the other, pins adapted to be passed through the opening of the meshing portions to rigidly connect the members, and means for locking the pins in position.

10. A protector for use on a string of equipment operating in a well and having longitudinally spaced projecting parts, said protector including, a resilient continuous annular body adapted to be sprung over one of said parts to a position on the string between said parts, a sectional annular reinforcement for the body and means for connecting the sections of the reinforcement after positioning of the body between 15 said parts to prevent radial expansion of the body.

11. A protector for use on a string of equipment operating in a well and having longitudinally spaced projecting parts, said protector including, a resilient continuous annular body adapted to be sprung over one of said parts to a position on the string between said parts, a sectional reinforcement embedded in the body, the sections of the reinforcement being rigid and substantially 25 semi-circular in horizontal cross section, and means for connecting the adjacent edge portions of said sections to prevent radial expansion of the body and displacement of the body from between said parts.

12. A well drilling string having longitudinally spaced projecting parts, a resilient continuous annular body adapted to be sprung over one of said parts to a position on the string between said parts, and means in the body for preventing radial expansion of the body after it has been positioned between said parts, said body being rotatable relative to the string.

35 13. A protector for use on a string of equipment operating in a well and having longitudinally spaced projecting parts, said protector including, a resilient annular body adapted to be sprung over one of said parts to a position on the string between said parts, and means for preventing displacement of the body from between said 40 parts including substantially rigid members molded in the body, projecting portions on the vertical edges of the members having vertical openings, said portions on adjacent edges of the member meshing one between the other, pins 45 adapted to be passed through the openings of the meshing portions to rigidly connect the members, and means for locking the pins in position, the last mentioned means including shoulders on the pins cooperating with said 50 meshing portions and holding the pins against longitudinal movement.

14. A protector for use on a string of equipment having spaced projections including a continuous annular body of resilient material presenting an unbroken circumferential surface, the body being adapted to be sprung over a projection to a position on the string between two projections, and means for preventing radial expansion of the body after it has been positioned between 65 projections.
